EXERCISING APPARATUS

Valentine C. Luppert, Williamsport, Pa.

Application December 10, 1931, Serial No. 580,138

14 Claims. (Cl. 272—83)

This invention relates to improvements in exercising machines and more especially to a novel exercising device of the type including spring retracted winding rollers.

One of the objects of the invention is to provide a machine of this type, including a pair of tapes which are wound by spring action on wheels or pulleys, the construction being such that either tape may be unwound independently of the other, or both tapes may be unwound and wound simultaneously.

Another object is to furnish such a machine in which the springs that cooperate with the tape pulleys may be simultaneously adjusted for properly tensioning the same so that the machine may be used by a child having little strength, or by a man of great strength.

A still further object is to provide an apparatus of this character, wherein the springs and tape rollers are of unitary construction to permit the unit to be mounted on a wall, floor, or on a base which may form an exercising machine of the rowing type.

Another object of the invention is to provide a spring unit for exercising machines, in which spring means may be employed in combination with each tape roller, each spring of said means having coils of substantially the same length as the shaft on which they are mounted.

A still further object is to provide an exercising machine of the rowing type, comprising improved means for retaining the seat on the tracks and for preventing the tracks from spreading or moving toward one another.

With the foregoing objects outlined and with other objects in view which will appear as the description proceeds, the invention consists in the novel features hereinafter described in detail, illustrated in the accompanying drawings, and more particularly pointed out in the appended claims.

In the drawings,

Fig. 1 is a top plan view of the entire machine partly in horizontal section.

Fig. 2 is a side elevation of the same.

Fig. 3 is a vertical sectional view on the line 3—3 of Fig. 1.

Fig. 4 is a transverse vertical sectional view of a detail on the line 4—4 of Fig. 3.

Fig. 5 is an enlarged longitudinal sectional view of the spring assembly or unit of the machine, taken on the line 5—5 of Fig. 6.

Fig. 6 is a vertical sectional view of a detail on the line 6—6 of Fig. 5.

Fig. 7 is a perspective view on a reduced scale, of the shell or cover of the spring assembly.

Fig. 8 is an end view of one of the tape rollers or pulleys.

Fig. 9 is an edge view of the same.

Fig. 10 is a view similar to Fig. 5, but showing a modification in which a single tape and roller only are used.

Fig. 11 is a perspective view of a modified form of cover or casing for the spring unit.

Fig. 12 is a view similar to Fig. 5 of a modification.

Fig. 13 is a view similar to Fig. 5, of a further modification.

Referring to the drawings, 15 designates one of my improved exercising machine spring units or assemblies. As best shown in Figs. 1, 3, 5 to 9 inclusive, such unit comprises a pair of circular end plates 16 provided with oppositely directed arms 17 that may be detachably connected to a wall, floor or exercising machine base. As illustrated in said figures, these end plates seat in semi-circular recesses 18 in the side bars 19 of a base, and the arms 17 are rigidly secured to said base by any suitable means which will permit detachment of the unit from the base. For example, the base may be provided with threaded shanks 20 to receive wing nuts 21 which clamp the arms to the forward ends of the side bars of the base.

A cylindrical shell or cover 22 for the unit has its ends seated in circular grooves 23 in the end plates, and in this way the cover is rigidly fastened to the end plates. The latter provides bearings 24 for a rotatable shaft 25 which has threaded ends protruding through the end plates and provided with nuts 26. One end portion of the shaft is of angular formation as shown at 27, and this portion of the shaft is rigidly secured by one of the nuts to a crank 28 having a handle 29. The handle accommodates a spring pressed plunger or latch 30 having a knob 31 at its outer end. The end of the plunger nearest the adjacent end plate forms a pin which may enter any one of a series of cavities 32 which extend in a circular series around one face of one of the end plates.

Washers 33 are provided between the nuts and the end plates to prevent the nuts from accidentally unscrewing when the shaft is turned. Pulleys 34 are rotatably mounted on the shaft adjacent to the end plates, and each pulley has a rim 35, a longitudinal slot 36, and a circular internal cavity 37. The slot of the pulley, among other things, permits the anchor 38 of

50

55

60

65

70

75

a wound tape 39 to be arranged within the cavity 37 while the tape itself extends through the slot, as best shown at 40 in Fig. 6. The opposite end of each tape is provided with a handle 41 as shown in Figs. 1 and 3.

The cavity of each roller receives one end of an outer coil spring 42, one extremity of which extends into the slot as shown at 43 for anchoring this end of the spring to the pulley. The 10 opposite end of the spring is anchored as shown at 44 in the peripheral slot 45 of a collar 46 which is rotatably mounted on the shaft. A washer 47 arranged between these collars permits either one of the same to rotate independently of the other.

For the purpose of preventing damaging or distortion of the spring 42 when the tape is unwound and the spring is wound, a stop tube 48 is arranged within the spring and has its ends 20 seated respectively upon the bosses 49 and 50 of the collar and pulley.

In order to obtain maximum spring action, a second spring 51 is arranged within the tube and has one of its ends anchored to the collar as 25 shown at 52, and its other end anchored to the fixed collar 53a, as shown at 53. An inner tube 54 prevents distortion of the inner spring.

As shown in Figs. 6 and 7, the cover or casing 22 is notched at 55 to allow the tapes to be 30 wound and unwound, and the springs arranged at one side of the washer 47 are right hand, and the springs arranged at the left are left hand. However, when the shaft 25 is turned by the handle 29, all of said springs may be simultaneously tensioned. Of course, if the device is 35 to be used by a child, slight tension only is used, and as the strength of the individual builds up, greater tension can be placed on the springs by operating the handle 29 and placing the plunger 40 pin in the proper hole of the end plate.

Regardless of whether such unit is mounted on a wall, ceiling, floor or other suitable supporting surface, it will be understood that when a pull is exerted on either one of the handles 41 45 and the tape 39 is unwound, its pulley 34 will act to wind the outer spring 42, and said spring in turn will rotate the collar 46 and cause winding of the inner spring 51, as the end 53 of the latter is prevented from turning by the fixed 50 collar 53a which is rigidly secured to the shaft. Of course, when pull on the handle 41 is diminished, the spring tends to unwind and the tape is rewound on its pulley.

A spring assembly or unit of this kind is particularly applicable to exercising machines of the rowing type. For instance, if it is placed on the side bars 19 of such a machine, these bars may be rigidly connected by a cross platform 56, and an end bar 57 to form a suitable base upon which 60 a seat 58 may reciprocate. In accordance with the present invention, the seat is provided on its under side with depending strips 59 and outer depending plates 60 in which the shafts 61 of suitable rollers 62 are journaled. Each of these 65 rollers has an inner flange 63 to bear against the beveled edge 64 of the side bar or track. This feature prevents the seat from shifting laterally outwardly. Each bar also has a longitudinal outer groove 65 to receive the flange 66 at the 70 lower end of the plate 60. This not alone prevents the bars from spreading apart, but prevents the seat from jumping the track as it is moved back and forth by the operator.

In operation, assuming that the operator is 75 sitting on the seat 58 with his feet resting on the

casing 22. If he moves his body and limbs in a manner similar to that of a person rowing, the tapes will be alternately wound and unwound, and at the same time, the seat will be moved toward and away from the spring unit. 5

Instead of using two tapes, as shown in Figs. 1 to 9 inclusive, all of the springs may act upon one tape. For example, as shown in Fig. 10, the shaft 25a is mounted and adjusted in the same manner as the one shown in Fig. 5, and in this instance, a pair of collars 53b are fixed to the shaft and mounted at opposite sides of a centrally disposed pulley 34a which is rotatably mounted on the shaft and acts as a spool for the tape 39a. In this instance, one end of each of the outer springs 42a is fixed to the central pulley and its other end is fixed to a collar 46a that rotates on the shaft. Inner springs 51a are also arranged about the shaft, and each of these springs has one of its ends 20 anchored to the fixed collar 53b, and its other end anchored to the rotatable collar 46a. Spring stop tubes 48a and 54a may also be used with this modification. Obviously, with this form of the invention, the opening 55a in the casing 22a 25 to permit the passage of the tape, must be arranged at the center of the casing.

If two tape pulleys or rollers are used, I may, instead of employing two springs for each pulley, employ a single spring as illustrated in 30 Figs. 12 and 13. In this embodiment, the shaft 25b is mounted and adjusted in the same manner as in Figs. 5 and 10, but here a collar 53c is fixed to the shaft as well as to a tube 48b. In this instance, each spring is of substantially the 35 same length as the shaft, and the inner spring 51b has one of its ends secured to the collar and its other end secured to one of the tape rollers 34b which is rotatably mounted on the shaft. Another collar 53d is fixed to the tube, and the 40 outer spring 42b has one of its ends secured to the collar 53d, and its other end secured to a tape pulley 34c which also rotates on the shaft. It will be obvious from the description of the 45 construction illustrated in Fig. 5, that when the tapes of Figs. 12 and 13 are unwound and then wound, the pulleys will in turn wind the tapes and permit unwinding of the springs.

Where it is possible to employ a shaft of sufficient length, I can use single springs for 50 each pulley, and each spring need only be about one-half the length of the shaft. For example, in Fig. 13, the shaft 25c has fixed thereto at its 55 medial portion, a collar 53e. Springs 42c and 42d are arranged at opposite sides of the collar, and their inner ends are fixed to the latter as shown at 42e. The outer ends of the springs are secured to the tape pulleys 34e which are 60 rotatably mounted on the shaft. In this embodiment also, a stop tube 48c may be employed to prevent distortion of each spring.

While I have disclosed what I now consider to be preferred embodiments of the invention in such manner that they may be readily understood by those skilled in the art, I am aware 65 that changes may be made in the details disclosed without departing from the spirit of the invention, as expressed in the claims.

What I claim and desire to secure by Letters Patent is:

1. An exercising device including a rotatable shaft, coil springs surrounding the shaft, one of said springs being wound from right to left and the other being wound from left to right, pulley means rotatably mounted on the shaft, said 75

1. springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs.

2. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, means for circumferentially adjusting the shaft for simultaneously and equally tensioning said springs, and means arranged between the springs and the shaft for preventing distortion of the springs when the latter are wound.

3. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs, the last mentioned means comprising a plate in which the shaft rotates, said plate having a circular series of apertures, a handle fixed to the shaft, and a latch engageable with any one of said apertures for latching the handle to said plate.

4. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, means for circumferentially adjusting the shaft for simultaneously and equally tensioning said springs, plates in which the shaft is journaled, and a casing joining the plates and surrounding the springs, shaft and pulley means, said casing being ported to permit the passage of said tape means.

5. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs, and inner springs arranged within the first men-

ly tensioning said springs, said pulley means including a pulley having a longitudinally extending slot for use in anchoring a portion of the tape means thereto.

6. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs, said pulley means including a pulley provided with an annular cavity into which one end portion of one of the springs extends.

7. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs, end plates in which the shaft is journaled, arms projecting from each end plate and radiating from said shaft, and means for detachably securing said arms to a suitable support.

8. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs, one spring being arranged at one side of the medial portion of the shaft, and the other spring being arranged at the opposite side of the medial portion of the shaft, each spring being substantially equal in length to half the length of the shaft.

9. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously and equally tensioning said springs, and inner springs arranged within the first men-

tioned springs and forming a portion of the means for operatively connecting the first mentioned springs to the shaft.

10. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously tensioning said springs, the tape pulley means comprising pulleys arranged at the opposite end portions of the shaft.

20 11. An exercising device including a rotatable shaft, coil springs surrounding the shaft, one of said springs being wound from right to left and the other being wound from left to right, pulley means rotatably mounted on the shaft, said
25 springs being operatively connected to said shaft and to the pulley means for causing winding of the springs when the pulley means is turned in one direction, tape means wound about the pulley means and adapted to be pulled by the
30 operator for rotating the pulley means in said direction, and means for circumferentially adjusting the shaft for simultaneously and equally tensioning said springs, the tape pulley means comprising a single pulley arranged at the me-
35 dial portion of the shaft.

12. An exercising device including a rotatable shaft, coil springs surrounding the shaft, one of said springs being wound from right to left and the other being wound from left to right, 40 pulley means rotatably mounted on the shaft, said springs being operatively connected to said shaft and to the pulley means for causing winding of the springs when the pulley means is turned in one direction, tape means wound about

the pulley means and adapted to be pulled by the operator for rotating the pulley means in said direction, and means for circumferentially adjusting the shaft for simultaneously tensioning said springs, each spring being of substantially the same length as the shaft and being positioned one within the other.

13. An exercising device including a rotatable shaft, coil springs surrounding the shaft, one of said springs being wound from right to left and the other being wound from left to right, pulley means rotatably mounted on the shaft, said springs being operatively connected to said shaft and to the pulley means for causing winding of the springs when the pulley means is turned in one direction, tape means wound about the pulley means and adapted to be pulled by the operator for rotating the pulley means in said direction, and means for circumferentially adjusting the shaft for simultaneously tensioning said springs, each spring being of substantially the same length as the shaft and being arranged one within the other, and a stop tube positioned between the springs.

14. An exercising device including a rotatable shaft, coil springs surrounding the shaft, one of said springs being wound from right to left and the other being wound from left to right, pulleys rotatably mounted on the shaft and movable independently of each other, said springs being operatively connected to said shaft and to the pulleys for causing winding of the springs when the pulleys are turned in one direction, tapes wound about the pulleys, each tape having one of its ends secured to one of the pulleys, handles connected to the other ends of the tapes and adapted to be pulled by the operator for rotating the pulleys in said direction, and means for circumferentially adjusting the shaft in a clock-wise or counter-clock-wise direction for simultaneously and equally tensioning or untensioning said springs.

VALENTINE C. LUPPERT.
